(57) **CLAIM**

The ornamental design for a ceiling fan blade iron, as shown and described.

DESCRIPTION

FIG. 1 is a perspective view from below of a ceiling fan blade iron in accordance with my design;

FIG. 2 is an enlarged perspective view from below of the ceiling fan blade iron in accordance with my design;

FIG. 3 is an enlarged bottom plan view of the ceiling fan blade iron in accordance with my design;

FIG. 4 is an enlarged top plan view of the ceiling fan blade iron in accordance with my design;

FIG. 5 is an enlarged side elevation view of the ceiling fan blade iron in accordance with my design; and,

FIG. 6 is an enlarged front elevation view of the ceiling fan blade iron in accordance with my design.

The broken lines showing environmental structure are for illustrative purposes and form no part of the claimed invention.
